(57) **CLAIM**

The ornamental design for a business card, as shown and described.

DESCRIPTION

FIG. 1 is a top perspective view of a business card showing our new design;

FIG. 2 is a top plan view thereof;

FIG. 3 is a front elevation view thereof;

FIG. 4 is a rear elevation view thereof;

FIG. 5 is a bottom view thereof;

FIG. 6 is a left elevation view thereof; and,

FIG. 7 is a right elevation view thereof.

The appearance of rectangular elements presented in broken line format designate areas of the business card for text, graphics, or indicia and forms no part of the claimed invention.

(Continued)

The appearance of round protrusion elements presented in broken line format represent environment and form no part of the claimed invention.

1 Claim, 3 Drawing Sheets
